CLAIM

We claim the ornamental design for a food package, as shown and described.

DESCRIPTION

FIG. 1 is a top perspective view of a first embodiment of a food package.

FIG. 2 is a left side view thereof.

FIG. 3 is a right side view thereof

FIG. 4 is a front view thereof.

FIG. 5 is a rear view thereof.

FIG. 6 is a top view thereof.

FIG. 7 is a bottom view thereof.

FIG. 8 is a top perspective view of a second embodiment of a food package.

FIG. 9 is a left side view of thereof.

FIG. 10 is a right side view thereof.

FIG. 11 is a front view thereof.

FIG. 12 is a rear view thereof.

FIG. 13 is a top view thereof.

FIG. 14 is a bottom view thereof.

FIG. 15 is a top perspective view of a third embodiment of a food package.

FIG. 16 is a left side view thereof.

FIG. 17 is a right side view thereof.

FIG. 18 is a front view thereof

FIG. 19 is a rear view thereof.

FIG. 20 is a top view thereof.

FIG. 21 is a bottom view thereof.

FIG. 22 is a top perspective view of a fourth embodiment of a food package.

FIG. 23 is a left side view thereof

FIG. 24 is a right side view thereof.

FIG. 25 is a front view thereof

FIG. 26 is a rear view thereof.

FIG. 27 is a top view thereof; and,

(Continued)

FIG. 28 is a bottom view thereof.

In FIGS. 8-14 and 22-28, stippling and straight-line surface shading represent contrast in materials.
